UNITED STATES PATENT OFFICE.

HOWARD CARPENTER MARMON, OF INDIANAPOLIS, INDIANA, ASSIGNOR
TO NORDYKE & MARMON COMPANY, OF INDIANAPOLIS, INDIANA, A
CORPORATION OF INDIANA.

OIL SYSTEM.

No. 810,959.

Specification of Letters Patent.

Patented Jan. 30, 1906.

Application filed February 13, 1905. Serial No. 245,421.

To all whom it may concern:

Be it known that I, HOWARD CARPENTER MARMON, a citizen of the United States, residing at Indianapolis, in the county of Marion and State of Indiana, have invented certain new and useful Improvements in Oiling Systems, of which the following is a specification.

The object of my invention is to provide means by which the several bearings of a shaft or a crank-shaft, the wrist-pins thereof, and both ends of the pitmen, carried thereby, and other bearings associated therewith may be supplied with oil under pressure, the arrangement being such that a single oiling mechanism will serve to supply all of the points requiring lubrication with an adequate supply of lubricant. To this end the oil is introduced into the end of an axial bore formed in the crank-shaft; and a further object of my invention is to provide a simple means through which the introduction may be made and of such character that no packing is required to prevent leakage and all leakage is returned to the pump.

The accompanying drawings illustrate my invention.

Figure 1 is a vertical section of an engine-casing, in which is mounted a four-crank shaft provided with my invention, the pitmen, their connected pistons, and the cylinders therefor being omitted for convenience of illustration. Fig. 2 is a section, on a larger scale, on line 2 2 of Fig. 1 with one of the pitmen applied. Fig. 3 is a detail section, on a larger scale, of the oil-introducing device. Fig. 4 is a detail, on a larger scale, on line 4 4 of Fig. 1. Fig. 5 is a vertical section of a desirable form of by-pass valve; Fig. 6, a section on line 6 6 of Fig. 5, and Fig. 7 a section on line 7 7 of Fig. 5.

In the drawings, 10 indicates the crank-shaft, of any desired form, provided with a plurality of wrist-pins 11 and suitable journals 12. Running through the crank-shaft and the several journals is a central bore 13, as shown in dotted lines in Fig. 1, with which communicate passages 14, formed through the wrist-pins and crank-arms. These passages may be formed in any manner well known in machine-shops, preferably by boring and plugging the open ends of the bores. Leading from the passage 13 outward

to the periphery of each journal 12 is a smaller discharge-passage 15, and leading to the periphery of each wrist-pin from the passage 14 is a small discharge-passage 16. The oil is introduced into the end of the crank-shaft 10 by the feeder. (Shown particularly in Fig. 3.) This feeder consists of a shell-like body 17, the main annular portion 18 of which is sleeved snugly over the end of shaft 10. The annular portion 18 has formed in its inner periphery a shallow thread or spiral groove 19, which leads inward from the open end thereof in the direction of rotation of the shaft 10. This spiral groove leads into an annular chamber 20, which discharges into a return-pipe 21. Brazed or otherwise suitably secured in the casing 17 concentric with the annulus 18 is a feed-tube 22, which has no communication with the chamber 20 and which fits the bore 13 of shaft 10 snugly and extends a considerable distance thereinto. This tube at its end and on its periphery is provided with a shallow spiral groove 23, which leads toward the end of the tube in the direction of rotation of the shaft. The casting end of tube 22 communicates with a chamber 24, formed in casing 17, and into this chamber leads a suitable supply-pipe 25.

Pipe 25 leads from the discharge-outlet 26 of a small pump 27. Said pump may be of any type, in the drawings being shown as consisting of a suitable casing, within which is mounted a pair of meshing gears 28 28, one of said gears being driven by means of a shaft 29, connected through a suitable separable clutch 30 with a shaft 31, which in turn may be driven by any suitable gearing with any rotating part of the engine structure—as, for instance, the cam-shaft 32—the present invention being shown in connection with a gas-engine structure, but of course not to be limited to such use. The pump 27 is provided with a suitable inlet-pipe 33, the end of which lies in the bottom of an oil-reservoir 34, into which the drippings from the various bearings to be oiled may flow. The overflow-pipe 21 leads into this reservoir.

Mounted upon each wrist-pin 11 is a pitman 35, which carries a tube 36, which forms a communication between the inner or wrist-pin end and the bearing at the outer end. In practice I provide the outer end with a suitable bushing 37, having an opening 38 there-

- through, which opening is adapted to register with the outer end of the tube 36, but is of less diameter than the diameter of the tube, the bushing 37 thus serving to hold the tube 36 against longitudinal displacement in one direction. For convenience in assembling the parts I have shown in Fig. 2 the wrist-pin end of the pitman provided with the usual removable cap 39 and the split bushing 40.
- 10 One-half of this bushing 40 is provided with an opening 41, which registers with tube 36, but is also of somewhat less diameter than the diameter of tube 36, thus serving to hold the tube against displacement in this direction.

- 15 The casing 17 is merely slipped over the end of the crank-shaft, as clearly shown in Fig. 3, and oil is forced by the pump through the tube 25 into chamber 24, and thence 20 through tube 22 into bore 13, through which and the passages 14 the oil is forced, and consequently is forced out through the small passages 15 and 16, so as to lubricate the journals and wrist-pins. At the same time 25 the oil is also forced through opening 41, tube 36, and opening 38 to the bearing at the farther end of each pitman, so that a constant stream of oil is continuously supplied under pressure to all of the bearings associated with 30 the crank-shaft.

- 35 It will be readily understood that passages may be led through stationary parts to any desired bearings from any of the journal bearings of the crank-shaft, if desired. Such a construction is illustrated at the left of Fig. 1, where a passage 50 is formed through the wall of the inclosing casing 51 and leading to the bearing 52 of the cam-shaft 32. A portion of the passage 50 leads transversely 40 through a stud-shaft 53, and formed in this stud-shaft is a longitudinal passage 54, (indicated by dotted lines,) which leads outward to a point beneath the gear 55, which is journaled thereon.

- 45 There is of course considerable pressure of oil in bore 13, and there is a tendency, therefore, for the oil to work out along tube 22. The spiral groove 23, however, causes most of this oil to be returned to the bore 13, for 50 the reason that the direction of rotation of the shaft 10 is such as to carry the oil in a groove 23 toward the inner end of the tube. If, however, the oil does pass outward along tube 22 and work out to the periphery of shaft 10, it is returned into chamber 20 by 55 the groove 19 and flows from thence through pipe 21 back to the reservoir. Actual tests have shown that with this apparatus the fit of tube 22 in bore 13 need not be tight and 60 that annulus 18 need only fit the shaft 10 fairly well; yet even then there is no leakage of oil from the feeder, but it all passes to pipe 21.

- 65 The amount of oil supplied to the bearings by the pump is dependent, of course, upon

the speed of the engine, and in order that at high speeds there may not be too much oil forced to the bearings I prefer to provide a by-pass valve in the pipe 25 in order that the delivery-pressure of the oil to the several 70 bearings may never exceed a desired amount. Any desired form of valve may be used, a convenient form of automatic valve being that shown in Figs. 5, 6, and 7, consisting there of a cylindrical shell 60, adapted to be 75 threaded into an ordinary T, fitting in the pipe 25. The shell 60 is provided with a suitable valve-seat 61, adapted to receive a valve member or ball 62. The ball 62 is normally urged to its seat by a suitable spring 80 63, which spring is supported upon the diverging arms of a cotter-pin 65. For convenience in manufacture the casing 60 is provided at its lower end with a transverse perforation 66 and a pair of nearly opposite perforations 67, the arrangement being such that the arms of the cotter-pin 65 may first pass together through the perforation 66 and then diverge, one arm passing through each of the perforations 67, thus forming a seat for 90 the lower end of the spring 63. Outlet-passages 64 are formed through the wall of the casing 60 immediately beyond the valve-seat 61, and the arrangement is such that when the pressure of oil in the pipe 25 exceeds the 95 strength of spring 63 the valve 62 will be temporarily forced from its seat, and the surplus of the oil discharged by the pump will be by-passed through the valve.

100 I claim as my invention—

1. In an oiling system, the combination, with a bored rotating member; of a feeder for introducing oil thereinto comprising, a main hollow casing provided with, an annulus arranged to slip over the end of the rotating member, a drip-chamber within the annulus, an inlet-chamber within the casing, a spiral groove formed in the interior of the annulus and leading in the direction of rotation of the shaft inward toward the drip-chamber, a tube 110 within the annulus communicating with the inlet-chamber and extending into the bore of the rotating member, there being a spiral groove on the periphery of the inlet-tube and leading toward the inner end thereof in the direction of rotation of the rotating member; and an overflow-pipe leading from said first-mentioned chamber.

2. In an oiling apparatus, the combination, with a bored rotating member, of a feeder for 120 introducing oil therein comprising; a main hollow casing provided with, an annulus arranged to slip over the end of the rotating member, a chamber within the annulus, an inlet-chamber within the casing, and a tube 125 communicating with said inlet-chamber and extending into the bore of the rotating member; and an overflow-pipe leading from the first-mentioned chamber.

3. In an oiling apparatus, the combination, 130

- with a bored rotating member; of a feeder for introducing oil thereinto comprising a main hollow casing provided with an annulus arranged to slip over the end of the rotating member, a drip-chamber within the annulus, an inlet-chamber, a tube communicating with said inlet-chamber and extending into the bore of the rotating member, there being a spiral groove formed in the interior of the annulus and leading in the direction of rotation of the shaft inward toward the drip-chamber; and an overflow-pipe leading from said drip-chamber.
4. In an oiling apparatus, the combination, with a bored rotating member; of a feeder for introducing oil thereinto comprising a main hollow casing provided with an annulus arranged to slip over the end of the rotating member, a drip-chamber within the annulus, an inlet-chamber, a tube communicating with said inlet-chamber and extending into the bore of the rotating member, there being a spiral groove running between the annulus and shaft inward toward the drip-chamber in the direction of rotation of the shaft; and an overflow-pipe leading from said drip-chamber.
5. In an oiling apparatus, the combination, with a bored rotating member, of a feeder for

introducing oil thereinto comprising, a main hollow casing provided with an annulus arranged to slip over the end of the rotating member, a tube arranged concentrically within said annulus and extending into the bore of the rotating member, and an inlet leading into said tube.

6. In an oiling apparatus, the combination of a tubular rotating member and a tubular feeder telescoping therewith, said two parts having, between their coacting surfaces, a spiral groove leading in a direction to prevent leakage.

7. In an oiling apparatus, the combination of a tubular rotating member, and a compound tubular feeder, the inner tube of said feeder telescoping within the tubular member and the outer tube telescoping over the tubular member, and an eduction-passage leading from the inner end of the outer tubular portion of the feeder.

In witness whereof I have hereunto set my hand and seal, at Indianapolis, Indiana, this 31st day of January, A. D. 1905.

HOWARD CARPENTER MARMON. [L. S.]
